UNITED STATES PATENT OFFICE

99,301

DESIGN FOR A BICYCLE HANDLE BAR EXTENSION STEM

Ewald F. Pawsat, Maysville, Ky., assignor to Wald
Manufacturing Company, Incorporated, a cor-
poration of Kentucky

Application June 15, 1935, Serial No. 57,285

Term of patent 14 years

To all whom it may concern:

Be it known that I, Ewald F. Pawsat, a citizen
of the United States, residing at Maysville, in the
county of Mason and State of Kentucky, have
invented a new, original, and ornamental Design
for Bicycle Handle Bar Extension Stems, of which
the following is a specification, reference being
had to the accompanying drawing, forming a part
thereof.

In the drawing:

Figure 1 is a front view of a bicycle handle bar
extension stem showing my new design.

Figure 2 is a side view of the bicycle handle
bar extension stem.

I claim:

The ornamental design for a bicycle handle bar
extension stem, as shown.

EWALD F. PAWSAT.
